UNITED STATES PATENT OFFICE.

BENJAMIN MYERS NUZUM, OF GRAFTON, WEST VIRGINIA.

REAMER.

No. 857,661.

Specification of Letters Patent.

Patented June 25, 1907.

Application filed February 11, 1907. Serial No. 356,667.

To all whom it may concern:

Be it known that I, BENJAMIN MYERS NUZUM, a citizen of the United States of America, and a resident of Grafton, county of Taylor, and State of West Virginia, have invented certain new and useful Improvements in Reamers, of which the following is a specification.

My invention relates to new and useful improvements in reamers, and it has for its object to provide an implement whereby both valves and valve-seats may be renewed, or refaced, and which is particularly adapted for dressing or refacing steam-nozzles to correct irregularities produced therein by wear and also for refacing the heads of injector-spindles, valve-disks, and the like.

As is well known, much trouble is experienced and much time is consumed in repairing valve-seats, valve-disks, the mouths of injector steam-nozzles, the heads of injector-spindles, and the like, which have become defective from wear, it being quite difficult to hold and guide the ordinary forms of reamers or refacing tools employed in such manner as to produce a perfect or effective seat.

By my invention a tool is provided by means of which perfect and accurate seats may be conveniently and quickly formed, said tool being adapted for refacing both valves and valve seats, interchangeable cutter-heads being employed.

In describing the invention in detail, reference is herein had to the accompanying drawings, forming a part of this specification, in which—

Figure 1 is a side elevation of the invention, showing an injector steam-nozzle mounted in position for refacing; Fig. 2 is a horizontal section of the same; Fig. 3 is a detail view of the removable nozzle-holder shown in Figs. 1 and 2; Fig. 4 is a cross section of a modified form of nozzle-holder showing a type of steam-nozzle mounted therein differing from that shown in Figs. 1 and 2; Fig. 5 is an enlarged detail view, partly in section, showing a valve-disk mounted for the refacing operation; and—Fig. 6 is an elevation of a modified form of cutter-head.

Referring to said drawings, in which like reference - numerals designate like parts throughout the several views—1 indicates a yoke having a pair of forwardly-extending parallel arms or yoke-members 2 and having an integral centrally-located rearwardly-directed boss 3, said yoke and boss having a

central threaded opening therethrough for the reception of an exteriorly-threaded sleeve-like guide or feed-screw 4. Provided in the inner or adjacent faces of the yoke-members 60 2 are oppositely-disposed transverse channels 5 adapted for receiving the opposite edges of a rectangular plate or nozzle-holder 6 which has a central circular aperture 7 therethrough. Said holder 6 is adapted for 65 having seated therein an ordinary type of steam-nozzle 8, the hollow stem or shank 9 of which projects through the aperture 7 from the inner face of the holder, while the usual integral collar 10 carried by the nozzle serves 70 as a shouldered bearing, resting against said inner face of the holder, as shown.

In use, the stem 11 of the ordinary injector-spindle is employed, the ordinary removable head or valve-disk which seats in the 75 steam-nozzle being removed from the integral threaded head 12 of said spindle and a convex cutter-head 13 substituted therefor, the said cutter-head conforming substantially in size to the removed head.

The operation of dressing the mouth of a steam-nozzle is substantially as follows: The operator, after substituting the cutter-head 13 for the ordinary spindle-head, inserts the stem 11 of the injector-spindle, rear end first, 85 through the guide or feed-screw 4 from its inner end. Then, having mounted or seated the nozzle in the holder 6 and having mounted said holder with its opposite edges in the grooves 5 of the yoke-members, said feed-screw is turned forward to exert a bearing 90 pressure upon the head 12 of the spindle or upon a collar 14 interposed between said feed-screw and said head. Then, employing a handle or crank 15 mounted upon the outer 95 end of the stem 11, said spindle is rotated. The refacing of the nozzle is effected through the contact of the rotating cutter-head with the nozzle mouth, the guide or feed-screw being screwed inward as the cutting 100 progresses. An angular head 16 is provided on the outer end of said feed-screw which facilitates the grasping of the latter with a wrench for effecting the turning thereof. The rotation of the nozzle is prevented by the provision in the nozzle-holder 6 of lateral recesses 17, in open communication with the central aperture 7, for the reception of the usual lateral lugs 18 carried by the type of nozzle illustrated in Figs. 1 and 2. When it 110 is desired to reface an injector steam-nozzle of a type in which the lateral lugs 18 are

omitted, but having an exteriorly-threaded portion or gland 19, as shown in Fig. 4, a holder 6^a having a screw-threaded aperture 7^a therethrough is provided, said gland being 5 screwed up tight within said aperture 7^a, as shown.

For dressing or refacing valves or the heads of injector-spindles 20, as shown in Fig. 5, the stem 11 of the spindle is mounted 10 as hereinbefore explained, and a concave cutter-head 21 is provided, the latter approaching the nozzle 8 in form in that it has a shank 9^b and lateral lugs 18^b for fitting in the holder 6.

15 It will be noted that a cutter, such as is shown in Fig. 6, might be employed for refacing valves and the like, said cutter consisting simply of a centrally-apertured plate 6^c having a concave cutting face 23 formed 20 therein, said plate being adapted for mounting in the grooves or channels 5 of the yoke-members 2.

It will be seen from the foregoing that I provide an extremely simple, inexpensive 25 and efficient self-centering implement or tool by means of which both valves and valve-seats may be quickly, conveniently and accurately dressed.

Having thus described my invention, what 30 I claim as new, and desire to secure by Letters Patent, is—

1. A device of the character described comprising a stem having a rotary cutter, a feed-screw embracing said stem, a yoke having parallel members in which are provided oppositely-disposed grooves, and a removable work-holder slidably held in said grooves, said holder being self-centering with respect to said cutter. 35

2. In a tool for refacing valves, valve-seats, injector-spindles, steam-nozzles, and the like, a revoluble spindle, a feed-screw for said spindle, a yoke in which said feed-screw is mounted, a pair of arms carried by said yoke in parallel alinement with said feed-screw, said arms being provided on adjacent faces with transverse grooves, a plate having its opposite edges slidably mounted in said grooves, said plate having a central aperture therein, recesses provided in said plate in 50 open communication with said aperture for the reception of the lateral lugs carried by a stem projected through said aperture, and a cutter for acting upon the part held between said arms. 55

In testimony whereof I affix my signature in presence of two subscribing witnesses.

BENJAMIN MYERS NUZUM.
